FRED NEHSMANN.

By Clarence O'Brien Attorney

UNITED STATES PATENT OFFICE

FRED NEHSMANN, OF NEW YORK, N. Y.

CLOTHES DRIER

Application filed May 28, 1930. Serial No. 456,550.

This invention relates to clothes driers, and more particularly it pertains to such devices as are capable of use in relatively small rooms and similarly restricted areas.

5 It is one of the objects of the present invention to provide a clothes drier of the clothes line type, which is especially adapted for use in small rooms such as apartment kitchens or the like.

10 It is another object of the invention to provide a clothes line which may be filled with articles of clothing to be dried, by a person standing upon the floor of a room and after it has been so filled, may be elevated to a position adjacent the ceiling of a room and out of the way of persons who may be walking around the room.

15 It is a further object of the invention to provide a device of the aforementioned character wherein a horizontally positioned clothes line may be raised or lowered, and at the same time may be maintained in a true horizontal plane, even though the raising and lowering force be applied to the clothes 20 line at one end only thereof.

25 Other objects of the invention relate to certain novel and improved constructions, arrangements and combinations of parts hereinafter described and particularly pointed out in the claims, the advantages of which will be readily understood and appreciated.

30 The invention will be clearly understood from the accompanying drawings illustrating the invention in its preferred form and the following detailed description of the construction therein shown.

35 In the drawings;

40 Figure 1, is a perspective view diagrammatically illustrating a clothes line and its operating mechanism constructed in accordance with the present invention,

45 Figure 2, is a detail fragmentary view partly in section taken on the line indicated by the arrow 2-2 in Figure 1; and

50 Figure 3, is a view partly in elevation and partly in section of a device constructed in accordance with the present invention.

55 In the present embodiment of the invention, the clothes line is designated by the reference numeral 10. The clothes line is con-

nected to two continuous members 5 and 6, as at 7 and 8 respectively. The clothes line 10, and the two continuous members 5 and 6 may be ropes or cable or similar flexible members, and the attachment of the clothes line 10 to the members 5 and 6 may be accomplished by knotting or tying at the points 7 and 8, but it is to be understood that suitable fastening means in the form of clips or the like may be employed at these points instead of knotting if desired.

60 The continuous member 5 travels around a lower pulley 11 and an upper pulley 12, and the continuous member 6 passes around a lower pulley 13 and an upper pulley 14. The lower pulleys 11 and 13 are of the single type, carried in brackets such as 15. As shown in Figure 2, the upper pulleys 12 and 14 are each mounted in a double bracket 16 and in each of said double brackets 16, there is carried a supplementary pulley, they being designated 17 and 18 respectively and the purpose of which will be hereinafter described.

65 From the foregoing it will be obvious that as the continuous members 5 and 6 are caused to travel about their respective pulleys 11, 12, 13 and 14, the clothes lines 10 will be raised or lowered as the case may be, dependent of course upon the direction of movement of the members 5 and 6.

70 Further it will be apparent that if the members 5 and 6 are moved simultaneously at the same rate of speed, the clothes line will at all times remain in a true horizontal plane.

75 Means is provided whereby the members 5 and 6 may be operated simultaneously in either direction, and at the same rate of speed, and this operating means is so constructed and arranged that it may be operated from a single point.

80 The operating means comprises two cords or ropes 20 and 21. The cord 20 is attached at one end as at 22 to the member 5, and extends over the pulleys 12 and 18, is attached as at 23 to the member 6, and hangs downwardly from the point of attachment 23 in a free end 24. The member 21 is attached as at 25, to the member 5, extends over the pulleys 17 and 14, is attached as at 26 to the member 6, and hangs down in a free end 27.

The operating members 20 and 21, being attached to opposite legs of the members 5 and 6, by a single operation of these members 20 and 21, the clothes line 10 may be 5 raised or lowered, the direction of movement of the clothes line depending of course upon which of the members is operated.

For example, with the clothes line in the 10 position illustrated in Figure 1, pull upon the member 20 through the medium of the member 24 will lower the clothes line. On the other hand, with the parts in the position shown in Figure 3, pull exerted upon the member 27 will effect a raising of the clothes 15 line. By reason of the various attachments of the operating members, the members 5 and 6 will be operated simultaneously, and consequently the clothes line will be raised or lowered in a true horizontal plane.

20 In installing the device, the several pulleys may be attached to suitable frame work carried by the walls of the room, to window frames, or in fact may be secured directly to the walls of the room in any desired manner.

While the invention has been herein illustrated in connection with a clothesline, it will be obvious that it may be used in other connections. For example the member 10 30 could, if desired, carry a curtain in front of a window, and operation of the device in the manner heretofore described, would effect a raising or lowering of the curtain as desired.

Having thus described the invention, what 35 I claim as new and desire to secure by U. S. Letters Patent, is:

1. A clothesline, a pair of spaced endless members to which said clothesline is attached at its ends, separate supporting means for 40 each of said endless members and means for simultaneously operating said endless members to raise and lower the clothesline.

2. A clothesline, a pair of spaced endless members to which said clothesline is attached 45 at its ends, separate supporting means for each of said endless members and means for simultaneously operating said endless members at the same rate of speed to raise and lower the clothesline, and maintain it in a true 50 horizontal plane during raising and lowering thereof.

3. A clothesline, comprising a pair of spaced endless members, separate supporting means for each of said endless members, a 55 pair of closely adjacent operating members, each being attached to both of said endless members, whereby to operate them simultaneously, and a clothesline attached at its ends to said spaced endless members said clotheslines being raised and lowered by the operation of said endless members.

4. A clothesline comprising a pair of spaced endless members, separate supporting means for each endless member, said supporting mean comprising a plurality of pul-

leys around which said member is adapted to run, the said pulleys being arranged in sets, and there being one set for each member, a clothesline connected at its ends to said endless members, operating members connected to said endless members, and pulleys around which said operating members run, said pulleys being so arranged that the operating members operate the endless members to raise and lower opposite ends of the clothesline 75 simultaneously.

5. A clothesline comprising a pair of spaced endless members, separate supporting means for each endless member and comprising a plurality of pulleys around which each endless member passes, said pulleys being arranged in sets there being one set for each endless member, a second set of pulleys, and operating members passing around said last mentioned set of pulleys, each of said operating members being attached to each of said endless members whereby to operate them simultaneously.

In testimony whereof I affix my signature.

FRED NEHSMANN.
